United States Patent Office

Des. 222,306
Patented Oct. 12, 1971

222,306

PENCIL

Perry Feuer, Roslyn, N.Y., assignor to Creative Creations, Inc., New York, N.Y.

Filed Sept. 23, 1970, Ser. No. 25,164

Term of patent 14 years

Int. Cl. D19—06

U.S. Cl. D74—24

FIG. 1 is a front view of a pencil showing my new design;

FIG. 2 is a side view thereof, the opposite side being substantially similar in appearance; and

FIG. 3 is a rear view thereof.

I claim:

The ornamental design for a pencil, substantially as shown and described.
